UNITED STATES PATENT OFFICE.

JAMES ALEXANDER JAMIESON, OF MONTREAL, CANADA.

STORAGE-BIN.

SPECIFICATION forming part of Letters Patent No. 752,841, dated February 28, 1904.

Application filed October 6, 1902. Serial No. 126,257. (No model.)

To all whom it may concern:

Be it known that I, JAMES ALEXANDER JAMIESON, of the city of Montreal, district of Montreal, Province of Quebec, Canada, have 5 invented certain new and useful Improvements in Storage-Bins; and I do hereby declare that the following is a full, clear, and exact description of the same.

My invention has reference to grouped bins 10 for use in the storage of granular substance; and it relates particularly to bins for this purpose made up of a series of plate-sections.

The feature of the grouped bins to which my invention has particular reference are the 15 means for bracing the bins and securing them together and the specific construction of the plates constituting the bin-walls.

The invention has for its object to strengthen the structure and increase the storage-space 20 in the group; and to this end I furnish each bin with a series of abutments, to which the bin-wall members are secured, said abutments being adapted to withstand the thrust of said wall members. These abutments each preferably 25 consists of a pair of vertical tie-plates located a short distance apart and connected at their vertical edges to each adjacent pair of bins, the space thus inclosed by each of said pairs of tie-plates and the portions between them of the adjacent pair of bins being filled with concrete or other filling, thus forming abutment-columns for rigidifying the bins, while the portions of the bin-walls between these columns are horizontally corrugated.

For full comprehension, however, of my invention reference must be had to the accompanying drawings, forming a part of this specification, in which like reference characters indicate the same part, and wherein—

Figure 1 is a side elevation of two contiguous bins connected together. Fig. 2 is a horizontal sectional view thereof, taken on line A B, Fig. 1. Fig. 3 is a top view of one of my improved plates before being set in place. Fig. 4 is a vertical sectional view thereof, and Fig. 5 is a detail enlarged sectional view illustrating a method of connecting the tie-plates

of my improved abutment-columns to the bins braced thereby.

My improved abutment-column consists, preferably, of a pair of tie-plates *b* of trough or channel cross-section, the flanges *c* whereof are rigidly connected, preferably by bolts *d*, to two of the standards *e* of each of the contiguous bins, the space inclosed by these tie-plates and the members or plates *f* of the bin-walls between them being filled with concrete, cement, or other filling *g*. The members or plates *h* other than those between these tie-plates are formed with horizontal corrugations *i*, extending across the middle of each and to within a short distance of each side edge, while said side edge portions *j* are plane to facilitate their connection to said standards *e* of the bin. This construction obviates the necessity of tie-rods across the interspaces *k* or subbins, while the corrugation of the middle portions of the members or plates *h* between the abutments allows of their being made of lighter material; and the same is the case with the plates *f*, which are braced by the concrete.

My improved abutment-columns, as above pointed out, comprise metal and concrete members and assist in carrying the vertical load and at the same time form rigid abutments to take the thrust of the arched plates *h* between them when the interspace bins are filled, and the corrugation of these plates stiffens them and maintains their radius.

What I claim is as follows:

1. In a bin structure, the combination with a series of abutment members, and a series of arched bin-wall members abutting at their ends upon said abutment members and arranged vertically with their convex sides facing inwardly.

2. In a bin structure, the combination with a series of abutment members grouped radially of a common point, and a series of arched bin-wall members abutting at their ends upon said abutment members and arranged vertically with their convex sides facing inwardly.

3. In a group of sheet-metal bins comprising main cylindrical bins and interspace bins the

combination with the metal walls of the main cylindrical bins, of a concrete column between each contiguous pair of said main cylindrical bins in a vertical plane extending through the centers of said main cylindrical bins, and means binding said metal walls and said concrete column together.

4. In a group of sheet-metal bins comprising main cylindrical bins and interspace bins the combination with the metal walls of the main cylindrical bins, of a combined metal and concrete column between each contiguous pair of said main cylindrical bins in a vertical plane extending through the centers of said main cylindrical bins, and means binding said metal walls and said concrete column together.

5. In a group of sheet-metal bins comprising main cylindrical bins arranged a short distance apart and interspace bins the combination with the metal walls of the main cylindrical bins, of a pair of vertically-arranged tie-plates disposed adjacent to one another between said main cylindrical bins and extending across the spaces therebetween, means connecting the vertical edges of said tie-plates to the walls of said main cylindrical bins, substantially as described and for the purpose set forth.

6. In a group of sheet-metal bins comprising main cylindrical bins arranged a short distance apart and interspace bins the combination with the metal walls of the main cylindrical bins, of a pair of vertically-arranged metallic members disposed adjacent to one another between said main cylindrical bins and extending across the spaces therebetween, means for connecting said vertical metallic members to the walls of said main cylindrical bins, and a concrete filling between said vertical members.

7. The combination with a pair of contiguous bins, of a pair of vertically-arranged tie-plates of trough or channel cross-section and disposed adjacent to one another between said bins, means for connecting the flanges of said tie-plate to the walls of said bins, substantially as described and for the purpose set forth.

8. The combination with a pair of contiguous bins having vertical bracing-standards, of a pair of vertically-arranged tie-plates disposed adjacent to one another between said bins, means for connecting the vertical edges of said tie-plates to the vertical standards of said bins, substantially as described and for the purpose set forth.

9. The combination with a pair of contiguous bins, of a pair of vertically-arranged tie-plates disposed adjacent to one another between said bins, means for connecting the vertical edges of said tie-plates to the walls of said bins, and a filling for the space between said tie-plates, substantially as described and for the purpose set forth.

10. The combination with a pair of contiguous bins having vertical bearing-standards, of a pair of vertically-arranged tie-plates of trough or channel cross-section and disposed adjacent to one another between said bins, means for connecting the flanges of said tie-plates to the vertical standards of said bins, and a filling for the space between said tie-plates, substantially as described and for the purpose set forth.

11. In a storage-bin the combination with a series of vertical bin-bracing standards, of a series of horizontally-corrugated arciform plate-sections secured between said vertical standards, substantially as described and for the purpose set forth.

12. A pair of vertical cylindrical bins having a series of vertical bin-bracing standards, a vertical series of horizontally-corrugated arciform plate-sections in each alternate space between said vertical standards, and a vertical series of plane arciform plate-sections in the intervening spaces between said standards, means for securing said plate-sections to said standards, and a concrete column between said bins and in contact with the plane plates of each bin and means for securing said bins to said columns, substantially as described and for the purpose set forth.

13. A pair of vertical cylindrical bins having a series of vertical bin-bracing standards, a vertical series of horizontally-corrugated arciform plate-sections in each alternate space between said vertical standards and a vertical series of plane arciform plate-sections in the intervening spaces between said standards, means for securing said plate-sections to said standards, a pair of tie-plates extending between said bins and secured at one side edge of each to the side edges of the plane plates of one of said bins and at their other side edges to the side edges of the plane plates of the other bin, and a filling between said tie-plates, substantially as described and for the purpose set forth.

14. A pair of vertical cylindrical bins having a series of vertical bin-bracing standards, a vertical series of horizontally-corrugated arciform plate-sections in each alternate space between said vertical standards, a vertical series of plane arciform plate-sections in the intervening spaces between said standards, means for securing said plate-sections to said standards, a pair of tie-plates of trough or channel cross-section extending between said bins and secured at one side edge of each to the side edges of the plane plates of one of said bins and at their other side edges to the side edges of the plane plates of the other bin, and a filling between said tie-plates, substantially as described and for the purpose set forth.

15. A pair of vertical cylindrical bins hav-

ing a series of vertical bin-bracing standards, a vertical series of horizontal corrugated arciform plate-sections in each alternate space between said vertical standards, and a vertical series of plane arciform plate-sections in the intervening spaces between said standards, means for securing said plate-sections to said standards and means for securing said bins to

10 said columns substantially as described and for the purpose set forth.

In testimony whereof I have affixed my signature in presence of two witnesses.

JAMES ALEXANDER JAMIESON.
